DOUBLE LIFT SHEDDING MOTION

Hugo Stäubli, Horgen, and Walter Wicker, Oberrieden, Switzerland, assignors to Gebr. Stäubli & Co., Horgen, Switzerland

Application June 24, 1953, Serial No. 363,865

Claims priority, application Switzerland
September 2, 1952

3 Claims. (Cl. 139—68)

The present invention relates to a double lift shedding motion in which, by means of suitable controlling devices, an endless pattern card of Verdol paper or similar thin material is used for controlling the drawhooks in order to bring them into the path of the lifting knives. It is desirable for a double lift shedding motion to be capable of running backwards, i. e. to pick out the weft in the right sequence by turning the shedding motion backwards; in other words if there is any fault in the fabric, it should be possible to weave backwards until the faulty pick lies in the open shed. If e. g. after twenty picks, a faulty pick in the 15th is discovered, it should be possible to turn the loom backwards in order to open the 20th shed and to take out the weft, then continuing the backward motion, the shed of the 19th pick is opened, then that of the 18th and so on until the shed of the 15th pick is reached and the weft concerned can be taken out. After this process, it should be possible to restart the forward motion of the loom in order to continue weaving. In case of double lift shedding motions that, as it is known, have two lifting knives or in case of double lift shedding motion with positive heald lifting device, two pairs of lifting knives, one of the knives or pair of knives lifts by means of drawhooks the healds for the even picks, whereas the other knife or pair of knives actuates the healds for the odd picks. The drawhooks are brought into and out of the path of the knives in either direction at the very moment when the knives are in their home position and as soon as the hooks have been set free. At that moment, the hooks have to be brought into such a position that they are either taken along by the knife or free of the latter in order not to be taken along; in other words, the healds are raised or remain in the lower shed as prescribed by the pattern card. The raising of the pattern card takes place by suitable means, determining the position of the hooks by means of intermediary members. Reading devices are known that allow a weaving backwards in the right sequence of the pick.

The present invention simplifies to a certain extent the already existing reading devices or removes disadvantages, characteristic to all former devices, such as the puncturing of the pattern card of Verdol paper. This invention relates to those double lift dobbies in which the movement of the pattern card of Verdol paper by two picks each time, takes place every second pick during the so-called lost motion, i. e. at the moment when one of the lifting knives or pair of knives is in a position to assure play between hooks and knife in order to enable the hooks to be controlled. According to the present invention, the shedding motion for controlling the hooks, provides for three reading needles per heald shaft, reading the pattern card as soon as the feeding of the latter is carried out and two driving bars, coacting with push needles, the latter actuating hook needles or suitable lifters, so that by means of rising bars, associated either to the hook needles or by direct motion, the hooks are brought into or out of the path of the lifting knives,

2

whereby the hooks which coact with the knife or pair of knives, in the lost motion of which the cylinder movement takes place, are associated with only one reading needle per hook and with a single driving bar and the

5 hooks which coact together with the other knife or pair of knives are associated with two reading needles and one driving bar with recesses and that this driving bar is submitted, apart from the lateral pushing movement in the direction of the needle, to a longitudinal to-and-fro movement, whereby the recesses in the driving bar occur at regular intervals corresponding to the lateral distances of the hooks and the extent of the to-and-fro movement corresponds to half the distance between two recesses.

10 15 The attached drawings give three constructional examples of the present invention:

Fig. 1 shows a vertical section on line II—II in Fig. 2 of the first constructional example of a double lift shedding motion with positive heald lifting device.

20 Fig. 2 shows a front view of Fig. 1 in which individual parts have been left out for reasons of clearness.

Fig. 3 shows a side view of the device according to Figs. 1 and 2.

25 Figs. 4 and 5 show a schematic side view of the second and third constructional example of a double lift shedding motion and

Fig. 6 finally shows the working diagram of the double lift shedding motion according to the first constructional example.

30 35 The present double lift shedding motion has frames 1 and 2 in which shaft 3 is supported. On shaft 3, swing levers 4 are placed in order to be capable of rocking. On pivots 5 of the swing levers 4, bars 6 are linked which lead to the lifting levers and the heald shafts which are not shown in the present drawing.

35 The baulk levers 8 are mounted so as to be capable of rocking on pivots 7 of the swing levers 4. The baulk levers are provided on both ends with double hooks 9 or 10 respectively. Double hook 9 coacts together with 40 the upper pair of knives 11, 12, double hook 10 with the lower pair of knives 13, 14. Two rods 15 and 16, displaceable parallel to themselves and extending over the whole width of this shedding motion may coact together with hooks 9 and 10, so as to press them against the knives 12 or 14 respectively. Rod 15 is supported by a 45 pair of levers 17 and rod 16 by a pair of levers 18, and the pairs of levers 17 and 18 rock on the fixed shaft 19 or 20. Rollers 21 or 22 on the pairs of levers 17 and 18 roll on cam discs 23 on each side of the frames 1 or 2, while the cam discs 23 are mounted on shaft 24 of the shedding motion. A draw spring 25 supports the levers 17 and 18 with the rollers 21 and 22, pressing them against the circumference of cam discs 23. The surface of abutment 26 or 27 respectively on double hooks 9 and 10 may coact together with lever 28 or 29, 50 mounted so as to be capable of rocking on shafts 30 and 31 respectively, subject to the influence of draw springs 32 or 33 respectively. These springs endeavour to press levers 28 and 29 with their surfaces of abutment 34 or 35 against the fixed stop rail 36 or 37.

55 The two stop rails 36 and 37 support toothed ledges 38 and 39 respectively in the recess of which push needles 40 or 41 and 42 are guided. Push needles 40 carry reading needles 43; push needles 41 carry reading needles 45 and push needles 42 reading needles 44. Push needles 40 and 41 coact together with push bar 46 and push needle 42 together with push bar 47. Push bars 46 and 47 are capable of a to-and-fro movement on rollers 48 or 49 respectively. Push bar 46 supports a toothed rail 50 with recesses at regular intervals, the distance of which is equal to the distance between two adjacent hooks and equal to the double distance between push needles 40 and 41. Push bar 47 is

provided with a full rib 51. Push bars 46 and 47 are connected by bar 52 or 53 respectively with swing lever 54 or 55 which in order to be capable of rocking are mounted on shaft 56, supported by the frames. The lower end of swing lever 54 supports two rollers 57 and 58, the axis of which being at right angles to each other and the rollers running on the circumference or on the lateral side respectively of cam disc 59 on a shaft 60. Swing lever 55 supports roller 61, running on cam disc 62 on shaft 60. Spring 63 presses rollers 57 and 61 against cam disc 59 or 62.

Push needles 40 and 41 rest on a cross bar 64 and push needles 42 on a cross bar 54.

The bars 64 and 65 are supported by arms 66 which are held at point 67 and mounted so as to be capable of rocking on arms 68, fixed on shaft 56. Shaft 56 is provided with a lever 69 (Figs. 2 and 3), supporting a roller 70, pressed by means of a spring 71 against a cam disc 72 on shaft 60.

Cam disc 72 is provided with a pin 73 which effects the movement of ratchet wheel 74 for pattern card cylinder 75. The pattern card cylinder 75 is placed on shaft 76 and carries pattern card 77. Certain parts in Fig. 2 have been omitted in order to give a better view of the other parts.

According to Fig. 3, knife 11 is mounted at both ends on each lever 78, whereby levers 78 are placed so as to be capable of rocking on shaft 79, mounted on frames 1 and 2. A guiding bar 81 grips bolt 80 of lever 78 and is linked at the other end with a bolt 82 of a lever 83. Lever 83 is placed so as to be capable of rocking on shaft 84, mounted on the two frames 1 and 2, and thereby supports a roller 85 which runs in groove 86 of curved disc 87.

Knife 12 is fixed on each side of the frames 1 and 2 to levers 88 and the latter are placed in order to be capable of rocking on shaft 79. A guiding bar 90 connects a pivot 91 on lever 88 with a pivot 92 on a lever 93. Lever 93, mounted so as to be capable of rocking on shaft 84, supports roller 95 which runs in groove 96 of curved disc 87, placed on shaft 24.

Knife 13 is fixed on each side of the frames 1 and 2 to levers 97 and rocks with these levers 97 on shaft 98. A roller 99 on lever 97 runs in groove 96 of curved disc 87.

Knife 14 is fixed to levers 100, mounted so as to be capable of rocking on shaft 98. A roller 101 on lever 100 runs in groove 86 of curved disc 87.

Shaft 24 takes its drive, as it is known, from the shaft of the loom and shaft 24 transmits its rotation on to shaft 69, not described herein.

The operation of the described shedding motion is as follows:

Pattern card 77 is read by three reading needles 43, 44 and 45 per heald shaft, whereby reading needles 43 and 45 read the even picks and needles 44 the odd picks. The raising of healds for the odd picks is operated by the lower pairs of knives 13 and 14 and the raising of healds for the even picks by the upper pairs of knives 11 and 12.

According to the present invention, as regards the lower pairs of knives, at the moment when the hooks are set free by the knives, the hooks have to be brought into or out of the path of the knives in such a manner that in the forward motion of the loom those hooks responsible for the raising of healds for the 13th pick, for example, must be taken along by the knife and in the backward motion of the loom those which are responsible for the raising of healds for the 11th pick. The same refers to the upper pair of knives where, in the forward motion, the hooks for the 14th pick and in the backward motion those for the 12th pick must be taken along by the knives.

Figs. 1 and 2 show the shedding motion in the position in which reading needles 43, 44 and 45 are removed from pattern card 77, the movement of the cylinder is half-finished, driving bars 46 and 47 are in their ultimate left position, so that in the continued turning of the shedding motion in one sense or the other, push needles 40, 41 and 42 drop on driving bar 46 or 47 in front of the toothed

rail 50 or rib 51 respectively and must therefore be carried along with them. This corresponds to the position of 120° in the diagram of Fig. 6. In the latter, the motional diagrams are designated by the same figures as the corresponding parts of the machine. Curve A shows the movement of needle supports 64 and 65, curve B the cylinder movement and curve C the lateral displacement of push bar 46. When the machine is then turned forwards, the cylinder movement is completely accomplished, so that 10 for instance the new picks, 12, 13 and 14 can be read. The reading process is accomplished at 160°. Driving bar 47 for the lower hooks 10 starts working at 160° having therefore actuated push needles 42 on lever 29, so that the corresponding hooks 10 are taken along by knife 13, which starts working at 190°. In the backward motion of 15 the machine, the hooks taken along by the lower pair of knives for e. g. the 13th pick are released at 190°. Shaft 16 for the lower hooks releases all hooks of the knife 13. At 160° the withdrawing of the reading needles begins, so that between 130° and 110°, the cylinder is turned 20 backwards and thus e. g. the picks 10, 11 and 12 can be read. The reading process finishes at 80° and push bar 47 starts working, so that by means of push needles 42, the hooks of the 11th pick are taken along by the lower pair of knives, which starts working at 50°. Regarding the even picks, actuated by the upper pair of knives 11, 12, the procedure is as follows: at 300° i. e. in the middle of the position of the knives in which hooks 9 were set free, the reading needles read picks 12 and 14, so that by means 25 of the movement of push bar 46 which starts working at 320°, push needles 41 actuate levers 28 and hooks 9, bringing them into the path of knife 11 which then sets to work. After the picks 12 and 14 which have been held ready by the reading needles, at 300°, the push bar 46 with recesses is shifted longitudinally in such a way that 30 in the forward motion of the machine at 320° push bar 46 is laterally displaced so that push needles 41 which are supported by reading needles 45 which carry out the reading of the 14th pick, are actuated by push bar 46, whereas as in the backward motion of the machine, push bar 46 is longitudinally displaced in such a manner that at 280° its position is such that push needles 40 which support reading needles 43, having read the 12th pick, are actuated. At 280° in the backward motion, the push bar starts 35 working, so that at 230° the corresponding hooks are brought into the path of the knives. In the forward motion, the push bar is put into action at 320°, so that at 10° the hooks are taken along by the knife and the shedding may take place either in one case or the other. By the coaction of three needles per heald shaft with two 40 push bars, one presenting recesses and being longitudinally displaceable and push needles actuating the drawhooks by means of levers, while the cylinder movement takes place during the lost motion of one pair of knives, the hooks for the following pick, in the forward motion of the machine, and the hooks for the preceding pick, in the 45 backward motion of the machine, are brought into the path of the corresponding knives.

The double lift shedding motion described herewith and given as an example in Figs. 1-3 is meant for double lift 50 shedding motions with positive heald lifting device and therefore shows two pairs of knives.

The control of the hooks according to the present invention is also applicable to double lift shedding motions as schematically shown in Figs. 4 and 5.

According to Fig. 4, three reading needles 102, 102' and 102'' which are controlled by the paper on the pattern cylinder 103, influence three push needles 104, 104' and 104'', one of which works on lifter hooks 105 and two on lifter hook 106 which are biased toward said push needles by springs 105' and 106' respectively. Lifter hooks 105 and 106 actuate, by means of hook needles 107, hooks 108 which coact together with knives 109, in order to turn the swing lever 110, thereby raising the heald shaft attached to the latter.

Push bars 111 and 112 actuate push needles in the

required sense for forward or backward motion of the machine, i. e. push bar 111 again is a toothed bar with recesses at intervals, equal to twice the distance between the two push needles 104' and 104''. When reading needles 102' and 102'' drop into holes, one or the other of the push needles 104' or 104'' is moved by means of a tooth of push bar 111. The reading needle 102 however, when dropping is always displaced by the rib of push bar 112.

According to Fig. 5, there are three reading needles 113, 113' and 113'', actuating the three push needles 114, 114' and 114'' which on their side coact together with two hook needles 115 and 115'. Hooks 116, according to their control, are brought by hook needles 115 and 115' into the path of the knives 117 in order to actuate swing lever 118 and in consequence the healds, not shown.

The displacement of push needles 114' and 114'' is carried out by means of push bar 119, having teeth 119' at intervals equal to twice the distance between the needles 114' and 114''. Push needle 114 may be worked by push bar 120 by means of a rib 120'. Springs 123, 123' and 123'' act respectively on push needles 114, 114' and 114'' urging them toward their respective push bars. In order to raise the hook needles, the raising bars 121 and 122 are provided. Apart from this, the working of this device is the same as that given in Fig. 4.

Having now particularly described and ascertained the nature of our said invention and in what manner the same is to be performed, we declare that what we claim is:

1. In a double lift shedding motion for a loom, a plurality of swing levers, means for connecting each of said swing levers to a heald, a pair of hooks connected with each of said levers, movable knives engageable with said hooks to impart movement to said hooks, levers and healds and means for controlling the engagement of said hooks with said knives comprising means for feeding a pattern card periodically every second pick during idle motion of said knives, a group of three push needles for each heald, means connecting one needle of each of said groups to one of said hooks associated with the respective heald to control the engagement of said hook with a

cooperating knife, means connecting the remaining two push needles of each group with the other of said hooks associated with the respective heald to control the engagement of said latter hook with a cooperating knife, push bars movable laterally of themselves to push said push needles, a reading needle carried by each of said push needles and engageable with the pattern card to position said push needles selectively in or out of position to be engaged by said push bars depending on the pattern, said push bar cooperating with said remaining two push needles for each heald having recesses at intervals equal to twice the distance between said push needles and means for shifting said last mentioned push bar longitudinally between a position in which it engages alternate ones only of said push needles, intervening push needles coinciding with said recesses, and a position in which it engages said intervening push needles only.

2. A shedding motion according to claim 1, in which said hooks are double-ended and a pair of knives cooperates with each hook.

3. In a double lift shedding motion, a series of draw hooks, means connecting said draw hooks with corresponding healds, a laterally movable knife engageable with said draw hooks and means for controlling the engagement of said draw hooks with said knife comprising two push needles connected with each of said draw hooks, a laterally movable push bar engageable with said push needles to actuate said needles, a reading needle carried by each of said push needles and engageable with a pattern card to position said push needles selectively in or out of position to be engaged by said push bar depending on the pattern, said push bar having recesses at intervals equal to twice the distance between said push needles and means for shifting said push bar longitudinally between a position for engaging alternate ones only of said push needles, intervening push needles coinciding with said recesses, and a position for engaging said intervening push needles only.
